UNITED STATES PATENT OFFICE.

HANS PEDER JENSEN, OF SAN FRANCISCO, CALIFORNIA.

BEET-HARVESTER.

1,102,272.

Specification of Letters Patent.

Patented July 7, 1914.

Application filed March 12, 1914. Serial No. 824,200.

To all whom it may concern:

Be it known that I, HANS PEDER JENSEN, a subject of the King of Denmark, residing at San Francisco, in the county of San Francisco and State of California, have invented certain new and useful Improvements in Beet-Harvesters, of which the following is a specification.

This invention relates to beet harvesters, and it has for its principal object to produce an organized machine of simple and improved construction whereby the beets will be lifted from the ground, conveyed in an upward and rearward direction, and whereby the leaves or tops will be detached, together with the upper succulent portion which I shall term the neck of the beet root, said neck being subsequently detached from the leaves, the latter being discarded. A further object of the invention is to produce a machine of the class described wherein in the conveying means shall be composed partly of cylindrical or approximately cylindrical brushes which are supported for rotation and which coöperate with other carrying means to support the beet while being carried in a rearward direction.

A further object of the invention is to simplify and improve the construction of the brushes and of the carrier coöperating therewith.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the drawings,—Figure 1 is a sectional elevation of a machine constructed in accordance with the invention, taken on the line 1—1 in Fig. 2. Fig. 2 is a top plan view of the same. Fig. 3 is a transverse section taken on the line 3—3 in Fig. 2. Fig. 4 is a view in side elevation of the beet lifter utilized in connection with the invention. Fig. 5 is a front view of the same. Fig. 6 is a perspective detail view of the clearing

knives which are utilized to separate the leaves from the neck of the root. Figs. 7, 8, 9, 10 and 11 are detail views of one of the links of the conveyer. Fig. 12 is a detail view illustrating a modified form of cylindrical brush member.

Corresponding parts in the several figures are denoted by like characters of reference.

The frame 15 of the improved machine is mounted on an axle 16 having ground wheels 17, said axle being supported for rotation so that power may be taken therefrom and conveyed to the moving parts of the machine.

Supported for rotation in the frame are two brush members 18, said brush members being preferably of the approximate configuration illustrated in the drawings, by reference to which it will be seen that said brush members are made tapering in two directions and that said brush members are so positioned with respect to each other that their axes will converge rearwardly and that their forwardly tapering portions will be so positioned that the lower portions thereof are substantially parallel to the surface of the ground and in contact therewith, or nearly so. When thus positioned it is evident that the forward ends of the two brush members will diverge with respect to each other so as to invite and facilitate the entrance therebetween of the leaves or tops of the row of beets that is being operated upon. The brushes, the tufts of which may be composed of any well known brush material, include in their construction the centrally located body members 19 on which the tufts are mounted tangentially, as will be seen by reference to Fig. 3. It will, furthermore, be seen that the tufts are arranged in spiral series with respect to the central members 19, as will be seen by reference to Fig. 2. For the purpose of transmitting motion from the axle to the brushes a counter shaft 20 is provided, said shaft receiving motion from the axle through the medium of an endless chain 21. The shaft 20 carries bevel gears 22 meshing with pinions 23 on the rear ends of the brush members which will thus be rotated when the machine is in motion, it being understood that the direction of rotation is as indicated by the arrows in Fig. 3, the lower parts of the brushes moving upwardly and inwardly. The brushes are to be mounted in such

90

110

tions of the two brushes will be substantially in contact with each other.

The frame supports in advance of the axle 13 a shaft 24, said shaft and the counter shaft 20 being equipped with chain wheels 25, 26 over which a conveyer chain C of special construction is guided. Said chain is composed of links which are shown in detail in Figs. 7 to 11, inclusive, said views representing, respectively, front, side, rear, top and bottom views of the links. Each link may be described as consisting of a plate 27 having at its forward end a rounded pivot lug 28 adapted to engage a recess 29 in the tail end of the preceding link, a shoulder or offset 30 being provided to abut on the preceding link to prevent the chain of which the links are composed from flexing in an upward direction. Each link is also provided with upwardly extending divergent prongs 31. The relative terms "upwardly", "front" and "rear" as here used apply to the upper lead of the chain, it being obvious that the lower chain lead occupies an inverted position. The chain links are joined together by means of pivots 32. It will be seen that the conveyer chain thus constructed and mounted presents an upper lead with forwardly extending prongs and a lower lead with rearwardly extending prongs; it will also be understood that while the chain is capable of flexing so that it may be trained over the supporting wheels, it is incapable of flexing in the opposite direction, thus keeping the leads of the chain taut and especially preventing the lower lead from flexing upwardly under the action of the brush members when the machine is in operation. It may here be mentioned that the brushes and the conveyer chain are preferably to be driven at such relative speed that, assuming a beet to be carried rearward by the lower chain lead, it will be engaged throughout by the brush tufts of the same spiral series, this being readily accomplished by properly proportioning the bevel gears 22 and 23.

A beet lifter 34 is provided, said beet lifter being supported by a shank 35 which, as best seen by reference to Fig. 5, is curved in such a fashion that it will support the lifter midway between the brushes and directly below the forward extremity of the chain conveyer, the upper extremity of the shank being attached to or connected with one side member of the frame.

Supported swingingly at the front end of the frame is a roller 36, the office of which is to crush down and slightly flatten the leafy tops of the beets to prepare them for engagement with the prongs of the conveyer chain.

Supported at the rearward end of the frame is a frame structure 37 affording bearings for the shafts of a pair of concave rollers 38 over which is guided an endless

conveyer 39 made of textile or other material. The frame 37 is supported for swinging movement so that the rearward or delivery end of the conveyer formed by the belt 39 may be swung to one side, as indicated in dotted lines in Fig. 2. The rearward portion of the frame likewise supports a rotary cutter 40 which, as well as the conveyer belt 39, receives motion from the counter shaft 20 in any convenient manner which may be substantially as indicated in the drawings, but which will need no detailed description. The axial shaft 41 of the rotary cutter is supported with respect to the chain conveyer C so that the operation of the latter will not be interfered with, and also preferably in such manner as to permit adjustment vertically, of the cutter so as to engage the roots at such distance below the leafy tops as may be desired.

Supported to the rear of the rotary cutter 40 is a clearing member or clearing cutter D, shown in detail in Fig. 6, and comprising a supporting shank 42 having divergent arms 43, the forward ends of which support upwardly and forwardly converging cutting members 44 which are placed at an angle substantially equal to the angle between the diverging prongs of each chain link, said prongs being practically engaged by the said cutting members. In Fig. 1 of the drawings the cutting members 43 have been shown as engaging the inner faces of the prongs, said cutting members converging between the prongs of the chain links. In Fig. 6 the cutting members have been positioned exteriorly with respect to the prongs 31, and I would have it understood that no limitation is intended with respect to the relative position of the prongs and the cutting members.

In Fig. 12 of the drawings a slight modification has been illustrated which consists simply in constructing each of the brushes of a plurality of sections, two such sections 46, 47 being indicated and said sections being independently revoluble. When such construction is used it is evident that motion is to be transmitted to said sections independently by any well known or convenient transmission means.

From the foregoing description, taken in connection with the drawings hereto annexed, the operation and advantages of this invention will be readily understood by those skilled in the art to which it appertains.

When the machine is drawn over the field, the roller 36 will beat down the leafy tops of the roots, not with the intention of crushing or breaking them, but merely with a view of flattening said tops so as to facilitate their subsequent engagement with the prongs of the chain conveyer C. The lifter which has been set to operate at a suitable

depth will now operate to lift the beets from the ground, the leafy tops being now engaged by the brushes which will sweep upwardly the said tops as well as the bodies of the beet roots until the tops become engaged by the divergent prongs 31 of the links of the conveyer chain, whereby the roots are now carried in a rearward direction. The upward sweep of the brushes against the beet tops and roots during their rearward transit will tend to maintain them securely and properly in position with their upper portions practically seated between the prongs. As the beet roots approach the rearward end of the machine, they will be engaged by the rotary cutter 40, being thereby severed, and the roots falling on the endless conveyer 39. This operation will leave the necks and the leafy tops of the beet roots still supported in the angles of the prongs which are next engaged by the clearing knives, which latter converge in the direction of the angles of the prongs, thereby serving to separate the leafy tops from the necks, the latter being permitted to drop on the chute 48, being thereby conveyed to one side. It is obvious that a receptacle may be provided for these neck portions which are extremely succulent and valuable for feed. The leafy tops are detached from the chain by the upward sweep of the rear ends of the brushes and are thereby thrown aside and on to the ground, the centrifugal action of the brushes being sufficient for this purpose.

It is obvious that the several moving parts of the machine may be driven at such relative speed as may be found most desirable; it may also be stated that simple adjusting means may be provided whereby the rotary brush members may be adjusted to compensate for wear.

It has been found in practice that one of the extremely desirable and advantageous features of this machine is that it will operate upon the beet roots without bruising or otherwise injuring them, causing them to lose their valuable juices.

It is to be understood that the brushes may be of any desired and convenient construction, no limitation being made to the use of "tufts" which would indicate the assemblage of the brush material in bunches; provided only that the brush material shall be of such a nature that it will flexibly or resiliently engage the crop, and more particularly the leafy tops of the beets in such a manner that as the brushes rotate they will exert a resilient upward pressure on the parts of the beets engaged thereby, thus serving to maintain the beet tops in engagement with the conveyer chain and the beet roots suspended in the proper position while in transit through the machine without injuring the skins of the roots, this being as-

sisted by the tangential arrangement of said tufts which has been herein described. Said tangential arrangement of the tufts also enables the brushes to clear themselves more readily of the leaves and waste matter than would otherwise be possible. This action is further due to the fact that the beet roots are in no wise impaled upon or injured by the prongs on the links of the conveyer chain, said prongs serving simply to engage the leafy tops and to afford a seat upon which the neck or top portion of the beet root is maintained by the upward sweep of the coacting brush members, the leafy tops being swept upward above the lower lead of the conveyer chain, while the beet root will gravitate to the approximate position shown in Fig. 1 of the drawings intermediate the front chain wheel 25 and the cutting apparatus.

It is desired to note that owing to the manner herein shown of mounting the tail conveyer for swiveling movement, it will be possible to deposit the beet roots extracted from a plurality of rows in a single row on the ground, thereby greatly facilitating the subsequent gathering of the roots, this being obviously made possible by proper adjustment of the conveyer at the beginning of each row.

Having thus described the invention, what is claimed as new, is:—

1. In a beet harvester, coacting flexible brushes supported for rotation and operating to exert an upward sweep on the leafy tops of beet roots extracted from the ground.
2. In a beet harvester, coacting flexible brushes supported for rotation and exerting an inward and upward sweep, and an endless conveyer coöperating with said brushes.
3. In a beet harvester, coacting flexible brushes supported for rotation and exerting an inward and upward sweep, an endless conveyer supported intermediate the brushes and having links provided with divergent prongs, and actuating means for the brushes and the conveyer.
4. In a beet harvester, coacting flexible brushes supported for rotation and having upwardly and rearwardly convergent axes, said brushes being tapering forwardly and rearwardly, and the lower portions of the forwardly tapering portions being substantially horizontal.
5. In a beet harvester, coacting flexible brushes supported for rotation and having an inward and upward sweep, the axes of said brushes converging upwardly and rearwardly, and said brushes having forwardly and rearwardly tapering portions, the lower portions of the forwardly tapering portions being substantially horizontal, and the rearwardly tapering portions of said brushes being substantially in contact throughout.
6. In a beet harvester, coacting flexible

brushes supported for rotation and having an inward and upward sweep, said brushes having rearwardly tapering substantially contacting portions, in combination with an endless conveyer supported intermediate said brushes, said chain having links adapted to seat the top portions of the beet roots and to engage the leafy tops thereof.

7. In a beet harvester, an endless conveyer chain having links provided with divergent prongs, in combination with rotary flexible brush members adapted to exert an upward sweep with respect to the lower lead of the chain, and actuating means for the conveyer chain and the brushes.

8. In a beet harvester, an endless conveyer chain comprising pivotally connected links, said chain being capable of flexing in one direction only, and said links being provided with divergent prongs, in combination with flexible brushes supported for rotation and exerting an upward sweep with respect to the lower lead of the conveyer chain, and actuating means for the brushes and the conveyer.

9. In a beet harvester of the character described, including an endless conveyer and flexible brushes supported for rotation and adapted to exert an upward sweep with respect to the lower lead of the conveyer, a gravity crushing roller supported in advance of the brushes to flatten the beet tops previous to engagement with said brushes.

10. A beet harvester comprising an endless conveyer chain, flexible brushes supported for rotation adjacent to the sides of the

lower conveyer lead and exerting an upward sweep with reference thereto, said chain having links provided with divergent prongs, means for severing the beets which are held in engagement with the prongs by the action of the brushes, and actuating means.

11. A beet harvester comprising an endless conveyer chain, flexible brushes supported for rotation adjacent to the sides of the lower conveyer lead and exerting an upward sweep with reference thereto, said chain having links provided with divergent prongs, means for severing the beets which are held in engagement with the prongs by the action of the brushes, and means for severing the leafy tops from the necks of the beets that are engaged by the conveyer chain after the severing of the beet roots.

12. A beet harvester in which is included an endless conveyer, beet lifting means, flexible brushes supported for rotation and adapted by an inward and upward sweep to move the lifted beets upwardly into engagement with the lower lead of the conveyer, beet severing means, and clearing means for separating the leafy tops from the necks of the beets that are retained in engagement with the conveyer by the action of the rotary brushes for the severing of the beet root.

In testimony whereof I affix my signature in presence of two witnesses.

HANS PEDER JENSEN.
